UNITED STATES PATENT OFFICE.

HERBERT H. BUNKER, OF JERSEY CITY, NEW JERSEY.

GRATING.

Application filed January 4, 1924. Serial No. 684,334.

This invention relates to gratings such as are adapted for use in floors, walk-ways, doors, jail cells, registers and areas although not restricted to such use, and has for one 5 of its primary objects the provision of a grating structure in which the component members or elements thereof may be readily assembled in such a manner as to effect an intimate unit thereof resulting in a strong, 10 compact, rigid, and durable unitary structure.

Other objects and certain advantages of the invention will become apparent from the following description when taken in connection with the accompanying drawings in 15 which—

Figure 1 is a fragmentary plan view of a grating embodying my invention.

Figure 2 is a transverse sectional view 20 taken on line 2—2 of Figure 1.

Figure 3 is a view similar to that of Figure 1 showing a modified form of the invention.

Figure 4 is a transverse sectional view 25 taken on line 4—4 of Figure 3.

Figure 5 is a view similar to that of Figure 4 showing a quantity of cement or other similar material moulded into the several spacing units.

30 Figure 6 is a view similar to that of Figure 4 showing the manner of inserting and securing a plurality of glass or other transparent blocks positioned within the several spacing units.

35 Figure 7 is a perspective view of one of the spacing units shown in Figure 1.

Figure 8 is a more or less diagrammatic view illustrating the method of locking to 40 each other the several spacing units shown in Figure 1.

Referring to Figures 1, 2, 7 and 8 of the drawings wherein is shown what I at present consider the preferred form of my invention the numeral 5 indicates a grating 45 comprising a plurality of spacing units or elements 6 coupled together and locked in their respective assembled positions in a manner hereinafter more particularly described. These units are preferably constructed from relatively heavy sheet metal and are bent into U-shaped members having bases 7 carrying at opposite ends thereof legs 8 to which are connected and preferably formed integral therewith a pair of 50 tongues or locking members 9. These tongues, as will be noted from Figure 7, are

so formed that their outer ends are of a width appreciably greater than the width of the tongues at their juncture with their respective legs 8. The base 7 of each of the units 6 is provided with a pair of openings 10 formed adjacent the legs 8 in proximity to their respective points of connection with the base. These openings are each of a width substantially equal to twice the thickness of the tongues 9 and are so formed that the tongues 9 will enter the openings only when the units are so positioned with respect to each other that the tongues 9 assume inclined positions or are disposed diagonally 60 with respect to the openings 10 as will be appreciated from an inspection of Figure 8. The grating is built up by linking the several spacing elements 6 together as shown particularly in Figure 1. After the elements have been assembled as shown, they are keyed together in an assembled relation as a unitary structure by means of longitudinally disposed parallel bars 11 which are passed through the several openings 10 in the space afforded adjacent the several tongues 9. These bars are of the same or substantially the same thickness as the tongues 9 and inasmuch as the openings 10 are in width approximately equal to twice the thickness of the tongues 9, it will be appreciated that a relatively tight fit of the several bars 11 is afforded with respect to the spacing elements 6. It will be further appreciated that such a fit between 65 the bars 11 and the several spacing elements 6 will result in the retention of the several spacing elements in their respective proper positions within a common plane. As above mentioned it is necessary, in assembling the several spacing elements, to so position them with respect to each other that the tongues 9 enter the openings 10 diagonally, such inclination being necessary for the reason that the outer ends of the tongues 9 are somewhat wider than the openings 10 are long. Once the tongues have been inserted into their respective openings 10 and the several longitudinal bars have been properly positioned, it becomes impossible to withdraw 70 the tongues 9 since they are held in their respective vertical positions within the openings by the longitudinal bars and are prevented from becoming dislodged due to the fact that they are keyed or locked against such displacement by reason of the fact that each tongue at its outer end is of a width 75

greater than the length of the opening within which the same is positioned. In order to further restrain the several spacing members 6 against relative movement either longitudinally or otherwise with respect to each other the longitudinally disposed parallel bars 11 may be bent over at corresponding ends as shown at 12 and into intimate engagement with a transversely disposed bar 13 which rests against the legs 8 of the spacing elements disposed at one end of the grating. It will be understood that the transverse bar 13 is provided with openings similar to the openings 10 but of only a sufficient width and length to receive and snugly fit the longitudinally disposed bars 11, one of such openings being indicated by the numeral 14. I have found by experiment that the outermost openings 10 of the outlying spacing element 6 may be equal in width to the remaining openings which are, as above mentioned, equal in width to twice the thickness of the single longitudinal bar 11, but if desired in practice the outermost openings 10 of the outlying spacing elements 6 may be equal in width to the thickness of a single bar inasmuch as these outermost openings are required to receive only the outermost of the longitudinally disposed bars 11.

Referring now to the modified form of my invention shown in Figures 3, 4, 5 and 6, the numeral 15 indicates, as a whole, a grating comprising a plurality of preferably square tubular elements 16, each of which is provided upon opposite sides with aligned openings 17 adapted for the reception of longitudinally disposed parallel bars 18. In assembling this modified form of grating the tubular spacing elements 16 are threaded upon longitudinally disposed parallel bars 18, the bars 18 being adapted to snugly fit the openings 17. After assembling the several units the same may be drawn into a more intimate relation by bending over or upsetting corresponding ends 19 of the longitudinally disposed bars 18 into engagement with the spacing elements that are carried upon the extreme ends of the bars.

In the event it is desired to mould a quantity of cement 20 into the several elements 16 as well as into the space afforded between these elements the spacing elements may be provided with openings 21 adapted for the reception of relatively short keying pins 22. These keying pins are of such lengths that the ends 23 thereof project into the spaces afforded between adjacent spacing elements 16 and become embedded into the concrete or cement 20 when the same is poured into the openings afforded between the adjacent spacing elements 16 whereas the main or body portions 24 of the pins become embedded into the concrete or cement which is moulded into and fills the several spacing

elements 16. It will be appreciated that the pins 22 so arranged provide an adequate support or keying means for the concrete, and being so keyed the concrete or cement functions, upon becoming set or hardened, to lend rigidity and strength to the grating in its entirety.

In the event it is desired to insert such light transmitting elements as glass or other transparent blocks 25 into the several spacing elements 16 the longitudinal edges of the longitudinally disposed bars 18 may be utilized as supports or seats for such blocks. These blocks as is customary may be secured in their respective positions by means of a suitable cement 26 applied as shown in Figure 6.

By employing the novel forms of spacing elements herein described I am enabled to effectively unite or lock them together by means of the longitudinally disposed bars hereinbefore described in such a manner as to form a unitary structure which is reinforced throughout its entire area against any strain, stress or impact which may be exerted thereupon or applied thereto at any given point. Such distribution of force is accounted for, as will be readily appreciated by those skilled in the art to which my invention pertains, by reason of the fact that the several spacing elements and longitudinal bars when united in accordance with my invention present a structure in which the component elements thereof are in effect integrally united. From an inspection of the structural units herein described it will be appreciated that the spacing elements function in effect also as transversely disposed bars or reinforcing members arranged perpendicularly to the longitudinal bars and also in effect as longitudinal stiffeners or reinforcing members cooperating with the longitudinally disposed bars herein described to lend further strength and rigidity to the structure in its entirety.

While I have shown and described what I at present consider the preferred forms of my invention, it will be understood that various changes in the size, arrangement and dimension of the component elements thereof may be changed without departing from the spirit of the invention or the scope of the subjoined claims.

Having thus described my invention I claim:

1. A grating comprising a plurality of spacing elements, each element having openings formed therein and being provided with a plurality of locking members, said elements being so arranged in the grating that said locking members on one element project into the openings of the adjacent elements.

2. A grating comprising a plurality of spacing elements, each element having open-

ings formed therein and being provided with a plurality of locking members, said elements being so arranged in the grating that said locking members on one element project into the openings of the adjacent elements, and additional means for locking said elements together in a unitary structure.

3. A grating comprising a plurality of spacing elements, each element having openings formed therein and being provided with a plurality of locking members, said elements being so arranged in the grating that said locking members on one element project into the openings of the adjacent elements, and means for locking said elements together in a unitary structure, said means being in the form of tying members passing through said openings.

4. A grating comprising a plurality of spacing elements, each element having openings formed therein and being provided with a plurality of locking members, said elements being so arranged in the grating that said locking members on one element project into the openings of the adjacent elements, and means for locking said elements together in a unitary structure, said means being in the form of tying members passing through said openings and maintained in engagement with said locking members.

5. A grating comprising a plurality of spacing elements, each element having openings formed therein and being provided with a plurality of locking members, said elements being so arranged in the grating that said locking members on one element project into the openings of the adjacent elements, and tying members passing through said openings, said tying members being distorted at corresponding ends to retain said spacing elements against movement with respect to each other and with respect to said tying members.

6. A grating comprising a plurality of

spacing elements having openings formed therein, said spacing elements arranged in rows, the spacing element of one row having means to interlock with cooperating means on the spacing elements of the two adjacent rows, and means for tying the spacing elements together.

7. A grating comprising a plurality of spacing elements arranged in rows, openings formed therein, each element being provided with locking members adapted to project into the openings of the element in the adjacent row, and means for holding the locking member of one element into engagement with the adjacent element.

8. A grating comprising a plurality of spacing elements, each element having an opening formed therein and having a locking member received within the opening in an adjacent member and additional means for locking said elements together, said means being in the form of tying members passing through openings in a plurality of said elements and maintained in engagement with said locking members.

9. A grating comprising a plurality of U-shaped spacing elements, each element having openings formed therein, the ends of said elements adapted to project into the opening of the adjacent element, and means for locking said elements together in a unitary structure.

10. A grating comprising a plurality of U-shaped spacing elements having openings formed therein, locking elements on the ends of said U, said elements being so arranged that the locking members on one element project into the openings of the adjacent elements, and tying members passing through the openings of said elements to lock the elements together in a unitary structure.

In testimony whereof, I have affixed my signature to this specification.

HERBERT H. BUNKER.
